Inventor:

George Topping

GEORGE TOPPING, OF CHICAGO, ILLINOIS.

Letters Patent No. 83,800, dated November 3, 1868.

IMPROVEMENT IN MITTENS.

The Schedule referred to in these Letters Patent and making part of the same.

To whom it may concern:

Be it known that I, GEORGE TOPPING, of Chicago, in the county of Cook, and State of Illinois, have invented a new and useful Improvement in Method and Patterns for Cutting Out Mittens or Gloves; and I do declare that the following is a true and accurate description thereof, reference being had to the accompanying drawings, and to the letters of reference marked thereon, and being a part of this specification.

Figure 1 is a plan view of my pattern.

Figure 2 is a perspective view of the same, when sewed together.

Like letters indicate like parts in each figure.

The object of this invention is to enable any one, by the use of my pattern, to cut out a mitten, so that, when cut out, it will be in one piece, thereby effecting a saving of material, and lessening the number and length of seams necessary to finish the mitten.

Should the material from which it is desired to cut the mitten be too small, or the wrong shape, the pattern may be folded upon the red lines in fig. 1, and the material be entirely used up by cutting each part separate.

A is the thumb;

B, the back;

C, the front; and
D, the ball of the thumb.

The superiority of this mitten over others is, that, when constructed of one piece, there are no seams in parts where there is any strain, and, consequently, there is no ripping.

After the mitten is cut, it is folded at the points shown in red, so that the edge E, of the thumb, will come in contact with and be sewn to the edge F of the face of the mitten. Commencing to sew at the points X, and following along the edges as they come, and sewing the same, the mitten is completed.

A gauntlet, of any desired form or material, may be attached to the wrist of the mitten, to give it a more comely appearance.

What I claim as my invention, and desire to secure by Letters Patent is—

Cutting the whole of a mitten, back, front, and thumb, out of one and the same piece of material, substantially as described and shown.

GEORGE TOPPING.
